Primary Examiner — Dominic V Simone(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is a front perspective view of an alternative embodiment of the shoe of FIGS. 1-3;

FIG. 5 is a side view thereof; and,

FIG. 6 is a rear perspective view thereof.

The broken lines immediately adjacent to the shaded areas define the bounds of the claimed design and form no part thereof. The oblique shade lines shown in FIGS. 4-6 represent transparency or translucency. The broken lines depicting the remainder of the shoe show features that form no part of the claimed design.
